UNITED STATES PATENT OFFICE.

JAMES G. SMITH, OF HACKENSACK, NEW JERSEY, AND CHARLES E. BUELL,
OF NEW HAVEN, CONNECTICUT, ASSIGNORS OF ONE-THIRD TO GEORGE
W. COY, OF MILFORD, CONNECTICUT.

SIGNALING APPARATUS FOR TELEPHONE-LINES.

SPECIFICATION forming part of Letters Patent No. 257,621, dated May 9, 1882.

Application filed March 3, 1882. (No model.)

To all whom it may concern:

Be it known that we, JAMES G. SMITH, of Hackensack, New Jersey, and CHARLES E. BUELL, of New Haven, Connecticut, have invented certain new and useful Improvements 5 in Signaling Apparatus for Telephone-Lines, of which the following is a specification.

Our invention relates to apparatus for employment at the central office of a telephone-exchange system; and the object is to provide 10 a simple and effective means whereby alternate positive and negative currents may be sent to any line of the exchange for operating suitably-constructed polarized electro-magnetic call-bells at subscribers' stations.

To this end our invention consists in the combination, with the telephone-exchange switch by which any two lines may be connected, of suitable means for connecting any 20 line of the exchange-system to a wire leading to the secondary of an induction-coil, and in the primary wire of said induction-coil constantly operating devices whereby a current flowing through the primary coil may be rapidly interrupted, reversed, or varied in such a manner as to produce in the secondary coil alternate positive and negative electric currents.

In conjunction with our invention we may use at the subscribers' stations polarized electro-magnetic call-bells of the ordinary construction, or of any other construction that may be found useful for the purpose of responding to rapidly-reversed line-currents.

The accompanying drawings illustrate some 35 of the many devices that may be employed in carrying out our invention.

Figure 1 illustrates the combination of the telephone-exchange switch with devices for producing the necessary changes of circuits, and 40 also shows one kind of apparatus for producing the changes in the primary circuit of the induction-coil necessary to the production of reversed currents in its secondary. Figs. 2, 3, 4, 5, 6, and 7 show modifications.

Referring to Fig. 1, N represents a telephone-exchange switch-board of any desired construction, that is adapted to connect the wires of any 45 two subscribers' lines.

W represents the polarized call-bell of a sub-

scriber's station, (here shown as consisting of a 50 horseshoe electro-magnet between whose poles vibrates a pivoted straight bar permanent, or electro-magnet w, carrying a bell-hammer.) The annunciators by which the line calling is indicated are shown at N'.

E represents the normal earth-connection of the subscribers' wires. Two lines only are here indicated for the sake of simplicity. Each line of the system is connected to the switch-board through a circuit-shifting apparatus, p, of any 55 suitable construction that is adapted to sever the connection of the line with the switch-board and normal ground and connect the line to a wire, 10, common to the lines and leading to the induction-coil apparatus by which the 60 reversed currents are produced, and, if desired, through a switch by which the wire 10 may be placed in connection with a telephone transmitter and receiver. S represents such a 65 switch adapted, as is indicated, to connect line 10 to telephone communicating apparatus M, and to break the connection leading to the secondary of the induction-coil.

A represents an induction-coil of any desired construction, whose primary coil is included in a local circuit with a battery, H, the 70 circuit of which is rapidly closed and broken by an electro-magnetic interrupter consisting of electro-magnet B, vibrating armature C, and contact-stop h, through which the circuit of a 75 local battery, F, is closed to the coils of the electro-magnet B.

D represents a spring-contact insulated from the armature-lever C, and adapted to come 80 into contact with a stop, b, when the armature is attracted by the electro-magnet B, and to thus complete the circuit of the induction-coil primary and local battery H, through d b, contact-spring D, and wire e, connected to contact-spring. When the armature C is drawn 85 against adjustable stop h by its retractor, contact at D, and therefore the circuit of local battery H, is broken, and at the same time the circuit of battery F through B is completed by standard f, contact h, armature-lever C, and wire e. Under this condition of the parts the armature C is immediately attracted by electro-magnet B, thus breaking the circuit of F 90 95

at the back contact of C, and causing the magnet B to be discharged, whereupon the retractor of the armature-lever acts and draws the armature back again into contact with the stop 5 h. Armature C is thus caused to vibrate. At every forward movement of the armature the spring D makes contact with h, thus completing the circuit of the battery for the primary of the induction-coil, while at every backward 10 movement contact between D and b is broken, thus breaking the circuit. Reverse electric impulses are thus rapidly and constantly produced in the secondary of the induction-coil, and when wire 10 is connected to any telephone-line the reversed currents will flow to line and cause rapid vibrations in the armature-levers of the polarized bells at subscribers' stations.

Instead of employing two local batteries, F and H, we may by another arrangement of 20 the circuits produce the same effects with one. Such an arrangement is shown in Fig. 2. Here standards f f and their contact-stops are connected to the same pole of local battery F, the other pole of which is connected through wire 25 a to the electro-magnet B, and through wire d to the primary of induction-coil. Armature-lever C and its insulated spring-contact D are, as before, connected respectively to electro-magnet B and to one end of the primary wire 30 of the induction-coil.

The operation is substantially the same as before described in connection with Fig. 1. When the armature-lever is drawn forward by the electro-magnet B the current from battery 35 F through the induction-coil flows through k, wire 9, b, D, c, d, while the circuit through electro-magnet B is interrupted at h. The armature being immediately retracted, the circuit of the primary coil is broken, and the circuit of 40 electro-magnet B is completed at h, and the operation is repeated.

Fig. 3 shows another arrangement, in which the flow of current through the primary of induction-coil is partially interrupted by completing a short circuit around it. When the armature of electro-magnet B is against its back contact-stop, h, the battery F flows in short circuit through electro-magnet B, armature C, contact-stop h, and standard f. When the armature is drawn forward the short circuit is 45 broken and the battery F flows to the primary through f c d. The interruption of the short circuit demagnetizes B, and the retractor of C immediately acts so as to draw the armature against contact-stop h and complete the short circuit again. The operation is thereupon immediately repeated, and rapid interruption of the short circuit ensues, thus causing the flow of current through the primary to be repeatedly interrupted, with the same results in the 55 secondary coil as before. It is of course necessary that the coils of magnet B should be of considerably less resistance than the primary coil, or that an artificial resistance should be 60 inserted in c or d.

Fig. 4 shows devices whereby the direction of current in the primary coil may be rapidly

reversed without interruptions to its continuity, thus producing at each reversal corresponding reversed currents in the secondary 70 of the induction-coil, wire 10, and any subscriber's line which is for the time being connected therewith. The device here shown resembles in its general characteristics a pole-changer, sometimes used in telegraphy. H 75 represents the local battery connected at one of its poles through a wire, x, with an insulated spring, r, mounted on a vertical post, and adapted, when relieved, to make contact with an insulated metallic hook connected by a wire, 80 m, with one end of the primary wire of the induction-coil. The other pole of the battery is connected by wire o with a similar spring, s, adapted to be carried by its resiliency into contact with an insulated metallic hook connected 85 by wire b with the same end of the primary coil as the hook first mentioned. The hooks and the springs are here shown as all insulated from one another, although it is evident that the two hooks might be electrically connected 90 through the supporting-post and a single wire run from the post in place of the wires m and d. C represents a vibrating lever kept in constant vibration by any suitable means—as, for instance, by the action of electro-magnet B 95 upon one side and a retractor upon the other, the circuit of a local battery through electro-magnet B being automatically made and broken through a back contact-stop, h, in a manner that is evident. To one end of the lever C is connected a conducting-pin, p, adapted or arranged as the lever vibrates to alternately press the springs r s out of contact with the hooks, so that first one and then the other completes a contact with a hook. When one spring is in 100 contact with a hook the other is pressed out of contact with its hook by the pin p, with which latter it is for the time being in electrical connection, and thus with the lever C, and through wire c, with the opposite end of 105 the primary wire from that with which wires m d are connected. When spring r is in contact with its hook the negative pole, say, of the battery H is in connection with one end of the primary coil through wire m, and its 110 positive pole is connected to the other end through s, p, and c. When spring s is in contact with its hook the positive pole of the battery is connected through wire d with that end of the primary coil to which the negative 115 pole was first connected, and the negative pole is connected to the other end through spring r, (which is now pressed back from its hook,) contact-pin p, and wire c. The direction of the current from battery H is thus by 120 the vibrations of lever C rapidly reversed, and corresponding reversed currents are produced in the secondary coil. Suitable adjusting-screws are employed in the well-known manner for securing the proper relation of the 125 parts. Other constructions of pole-changer may obviously be substituted for that here 130 shown.

Fig. 5 shows a well-known construction, in

which the core of the induction-coil takes the place of the electro-magnet B for vibrating the lever by which the desired changes in the local current flowing through the primary coil 5 are produced. C' represents an armature-lever, the armature of which is presented to the end of the induction-coil core. The circuit of the primary coil and its battery F' is through wire e, primary coil, wire a, lever C', and, when 10 the armature-lever is against its back contact-stop, through stop h and wire d, to the battery. When the lever is in this position the core of the induction-coil attracts it and draws it forward, so as to break the circuit at h, 15 whereupon the core loses its magnetism and the retractor of the armature immediately pulls it back again into contact with its stop, and the operation is repeated. As is evident, the makes and breaks of contact at h also produce 20 the necessary interruptions of current in the primary coil. If the lever C' be made to operate a pole-changer for reversing the primary-coil current, it is obvious that its armature should be polarized.

25 Fig. 6 shows a modification in which two reversely-wound primary coils are employed, and the current is caused to flow through first one and then the other. C is the vibrating lever, kept in vibration by electro-magnet B 30 and retractor in the manner before explained or in any other suitable manner. The end of the lever plays between two contact-stops, 7 and 8, forming the terminals of the reversely-wound primary coils, and is itself connected to one 35 pole of a battery, the other pole of which is connected to a common return-wire for the primary coils. As the lever vibrates, the current from the battery is caused to flow alternately through the reversely-wound coils, and to thus 40 induce alternate positive and negative currents in the secondary coil. Other modifications will readily suggest themselves to those skilled in the art. Instead of electro-magnetic devices for keeping the battery-controller C in 45 vibration, other means may be employed—as, for instance, a mechanically-driven train of wheels connected to an escapement-wheel whose escapement-lever forms the vibrating controller. Fig. 7 indicates such a modification. B' is an escapement-wheel kept in constant rotation by any suitable means, and C² is

an escapement-lever kept in constant vibration thereby. The lever C² controls the circuits of the primary in any of the ways before explained or in any other suitable manner. 55

Many other mechanical devices may obviously be employed for vibrating the lever. The rate of vibrating of the lever may be adjusted in any of the well-known ways. An adjustable weight, for instance, might be placed upon 60 the lever. In the case of the electro-magnetic devices for vibrating the lever the adjustment of the contact-screw through which the circuit of the operating electro-magnet is completed will serve to accomplish the purpose. 65

What we claim as our invention is—

1. The combination, substantially as described, with the central-office apparatus of a telephone-exchange system for placing any two subscribers' lines in connection with one another, of circuit-shifting apparatus for connecting any line to the secondary of an induction-coil, and in the primary circuit of the induction-coil a constantly-operating circuit-controller, whereby the current for the primary coil 70 is suitably varied, reversed, or controlled in such a way as to produce reversed currents in the secondary coil and the connected subscriber's line. 75

2. The combination, substantially as described, of the telephone-exchange switch, circuit-shifters in the line-circuits, a wire or connection common to said circuit-shifters, an induction-coil whose secondary forms a portion of said common wire or connection, and a constantly-operating circuit-controller for the primary circuit of the induction-coil. 80

3. The combination, substantially as described, of the telephone-exchange switch, circuit-shifters for connecting any line to the secondary of an induction-coil, and in the primary circuit of the induction-coil a constantly-operating pole-changer. 85 90
